ATTORNEY

UNITED STATES PATENT OFFICE

HARRY C. MALLORY, OF NEW YORK, N. Y.; SUE R. MALLORY ADMINISTRATRIX OF
SAID HARRY C. MALLORY, DECEASED

ENGINE-COOLING SYSTEM

Original application filed July 22, 1921, Serial No. 486,635. Divided and this application filed March 23, 1923. Serial No. 627,014.

My present invention consists in an improved method of and apparatus for cooling especially devised for use in cooling the cylinders of internal combustion engines used 5 on automobiles, aeroplanes and the like. The general object of my present invention is to provide an effective method of and apparatus for the purposes specified characterized by the provisions made for obtaining 10 a forced flow or circulation of cooling liquid through the engine cooling jacket or other cooling receptacle under conditions tending to eliminate or minimize the formation of air and vapor pockets in the jacket, 15 and for vaporizing a portion of the cooling liquid outside of the jacket, and for dissipating the necessary heat in a condenser in which the vapor produced is condensed. Preferably the circulation through the jacket 20 is regulated by varying the temperature, or rate of flow, or both temperature and rate of flow of the cooling liquid entering the jacket so as to maintain an approximately constant temperature in the upper and hot- 25 test portion of the latter notwithstanding variations in load or the temperature of the external atmosphere.

In a preferred mode of carrying out the invention, I pass both the vapor generated 30 and all or a portion of the cooling liquid not vaporized by heat absorbed in the engine jacket directly into the condenser, from the hotwell of which the mixture of un- 35 vaporized liquid and liquid of condensation formed in the condenser are returned to the jacket by a suitable circulating pump, and maintain a liquid pressure in the jacket appreciably higher than the pressure maintained in the condenser so that when the 40 pressure of the liquid is reduced in its passage from the jacket to the condenser a portion of the liquid bursts into vapor. I provide means for automatically regulating the circulation so as to maintain the desired 45 approximately constant temperature at the top of the jacket. This I accomplish by increasing or decreasing the temperature of the water returned to the jacket from the condenser as required to maintain the de- 50 sired temperature in the jacket.

In my application, Serial No. 486,635, filed July 22, 1921, of which the present application is a division, I have disclosed and generically claimed various methods and arrangements for regulating the temperature 55 at which the cooling liquid is supplied to the jacket inlet. In the arrangement specifically claimed in the present case, I employ a bypass connection about the condenser between the jacket outlet and pump inlet, and 60 thus make the liquid passed to the jacket inlet, a mixture of relatively hot liquid supplied through the bypass, and of relatively cool liquid drawn from the condenser hotwell, in proportions which may be varied 65 automatically in response to conditions of operation, as by means of a thermostatically controlled valve mechanism.

The various features of novelty which characterize my invention are pointed out 70 with particularity in the claims annexed to and forming a part of this specification. For a better understanding of the invention, however, and the advantages possessed by it, reference should be had to the accompanying drawings and descriptive matter in 75 which I have illustrated and described a preferred embodiment of my invention.

Of the drawings:

Fig. 1 is an elevation with parts broken 80 away and in section of an automobile engine equipped with my improved cooling system;

Fig. 2 is a section on the line 2--2 of Fig. 1; and

Fig. 3 is a sectional elevation of a portion 85 of the piping and control mechanism employed in Fig. 1.

In the apparatus shown, A represents the cooling liquid jacket for the cylinders A⁵ 90 of an ordinary internal combustion automobile engine. An inlet A' is provided at the bottom of the jacket space for the cooling liquid which will ordinarily be water, or a water and alcohol mixture. A² represents 95 an upper outlet from the jacket. As shown the outlet A² opens from the end of the jacket space near the top. The jacket outlet A² is connected to the top of a condenser C by piping comprising sections B, B¹, and 100

B². The section B² forms in effect the body of an expansion nozzle the throat orifice of which is formed by a plate b having a central orifice b'. As shown the orifice plate b is bolted between the adjacent flanged end portions of the piping sections B' and B². As shown the nozzle B² is frusto-conical in form and opens into the top chamber C² of the condenser C.

10 The condenser C is shown as comprising a group of horizontally disposed condensing tubes C' expanded at their ends and connected together, the condenser being in this respect as it may be in its entirety, similar 15 in construction to the ordinary air cooled radiator employed on an automobile having the ordinary water circulating engine cooling system. Advantageously, however, the condenser C is of the special construction 20 shown, having the bank of tubes C' spaced away from the top edge of the condenser to provide the chamber C², and spaced away from the bottom edge of the condenser to provide a hotwell C⁴, and spaced away from 25 the side edges of the condenser to provide steam distributing and water flow channels C³ extending vertically downward from the chamber C² to the chamber C⁴. A baffle C⁵ covers the top of the bank of tubes C' and 30 serves to divert the unvaporized liquid and vapor entering the condenser from the nozzle B² to the channels C³. Advantageously rain plates C⁶ are arranged within the bank 35 of tubes as shown to divert water of condensation formed in the intertube space above these rain plates into the channels C³.

40 D represents the outlet pipe for liquid running from the hotwell space C⁴ of the condenser to the inlet of the circulating pump E. The outlet from the latter is connected by a pipe D' to the jacket inlet A'. A check valve D¹⁰ in the pipe D prevents the jacket A from draining into the 45 hotwell of the condenser when the circulating pump stops. The circulating pump, which may be of the rotary type commonly employed as a circulating device in liquid cooling systems, may be driven from the 50 engine shaft by the reduction gear E' which, through the belt G', also drives a fan G for drawing air through the open ended tubes C'.

55 In the construction illustrated air is withdrawn from the condenser by means of an air pipe H running from the condenser to the suction intake manifold A³ of the engine or other air exhausting device capable of exerting the desired suction on the pipe H. As shown the pipe H extends into the condenser and is provided within the latter with an orifice H' at its under side through which air may pass out of the condenser but into which water of condensation will not fall. The pipe H may include an air valve

I preventing the outflow of steam and water, while permitting the escape of air from the condenser through the pipe H.

The valve casing B¹⁰ comprises a chamber B¹¹, forming a thoroughfare between the pipe sections B and B², and a second chamber B¹² connected to the chamber B¹¹ by the valve seated port B¹³. The chamber B¹² in conjunction with a pipe B¹⁴, forms a bypass about the condenser and the expansion nozzle section B² to the inlet side of the pump E. The check valve D¹⁰ is placed in the pipe D between the condenser and the junction with the pipe D with the bypass B¹⁴. The flow through the bypass is controlled by a valve member K¹¹ carried by an expansible bellows thermostatic element K¹⁰ located in the thoroughfare B¹¹. In the particular construction shown a stem J¹¹ connects the valve member K¹¹ to the end 85 of a bellows K¹³ located in the chamber B¹² and having its lower end anchored to the corresponding wall of the chamber B¹². The purpose of the bellows K¹³, which is of the same diameter as the bellows K¹⁰, is to minimize the effect on the thermostatic valve mechanism of pressure fluctuations in the 90 pressure of the circulating liquid.

In the contemplated mode of operation of the apparatus shown, the valve K¹¹ will be 95 off its seat and the liquid leaving the jacket will pass wholly, or mainly, back to the jacket through the bypass pipe B¹⁴, so long as the temperature of the liquid leaving the jacket is below that which the apparatus is 100 designed to maintain. When the liquid leaving the jacket rises to the maximum value desired, the thermostat K¹⁰ expands and seats the valve K¹¹, whereupon more or less of the liquid is diverted from the bypass into 105 the condenser C. The pressure of the liquid leaving the jacket through the outlet A² is reduced as the liquid passes through the piping B, B¹⁰ and B², the bulk of the pressure drop occurring at the orifice b' in the particular construction illustrated. When this 110 reduction in pressure occurs, a portion of the liquid, when heated as it will be in normal operation, is converted into vapor, and the unvaporized residue of the liquid is 115 cooled to the temperature corresponding to the temperature of the saturated vapor of the liquid at the pressure maintained in the condenser. The amount of liquid passing through the orifice b' which is converted 120 into vapor will depend, of course, on the difference between the temperature of the liquid leaving the jacket and the temperature of saturated vapor of the liquid at the 125 pressure in the condenser. The provision of the expansion nozzle B' avoids an excessive velocity of steam and liquid discharge into the condenser. The liquid and vapor entering the condenser C are directed from the chamber C² thereof into the channels C³ 130

from which the vapor passes into the inter-tube space of the condenser and is condensed, while the unvaporized liquid entering the top of the channels C^3 passes through the latter into the hotwell C^4 into which the liquid of condensation formed in the condenser eventually accumulates and from which the mixture of unvaporized liquid entering the condenser and liquid of condensation formed therein is returned to the jacket.

In practice the apparatus should be so designed that the condensing and cooling effect of the condenser C will be ample to make the condenser hotwell temperature at least as low as the minimum temperature at which the cooling liquid should be passed into the engine cooling jacket under any condition of operation. The temperature of the liquid passed by the pump E to the jacket inlet A' , will depend on the temperatures and relative volumes of the comparatively hot liquid passing to the pump inlet through the bypass B^{14} , and of the relatively cool liquid passing to the pump inlet from the condenser hotwell. A reduction or increase in the temperature at which the cooling liquid is passed into the jacket tends, of course, to a reduction or increase in the temperature of the cooling liquid when it leaves the jacket.

The condenser C may be operated at all times under a vacuum, but the jacket temperature is not dependent on the exact degree of vacuum maintained provided, of course, that it is sufficient to furnish the maximum cooling effect required. Advantageously, however, a vacuum relief valve L is provided which opens and admits air to the condenser when the vacuum therein exceeds the predetermined amount. In normal operation, the valve K^{11} and the valve L , when the latter is employed, will each normally be "cracked" so as to permit the restricted flow past the valve K^{11} required to obtain the desired regulation.

The temperature which the thermostatic element K^{10} is set to maintain in normal operation, will ordinarily be somewhere between 150° and 190° F., though a temperature higher or lower than this range can be maintained, if considered necessary, and in particular a temperature above 212° F. may be employed if desired. When the jacket temperature to be maintained is appreciably above 212° F. the pressure in the condenser may be equal to or above that of the atmosphere, and in such case the vacuum relief valve L need not be employed, and the outlet from the air valve I need not be connected to an air exhausting device.

Regardless of the cooling jacket temperature maintained, and notwithstanding the admission of air to the condenser through the vacuum relief valve L from time to time,

the air exhausting connection from the condenser insures in the regular operation of the apparatus that the water in the engine jacket space is practically air free. This desirably minimizes to a substantial degree the formation of air pockets and consequent hot spots in the engine jacket.

While in accordance with the provisions of the statutes I have illustrated and described the best forms of my present invention now known to me, it will be apparent to those skilled in the art that changes may be made in the form of my invention without departing from the spirit of my invention as set forth in the appended claims, and that certain features of my invention may sometimes be used to advantage without a corresponding use of other features.

Having now described my invention, what I claim as new and desire to secure by Letters Patent, is:

1. The method of engine cooling which consists in passing a cooling liquid through the engine jacket, dividing the liquid leaving the jacket into two portions, reducing the pressure of the liquid in one of said portions and thereby converting some of that portion into vapor, condensing said vapor, mixing the resultant liquid of condensation and the unvaporized residue of said one portion of the liquid with the other portion of the liquid, and returning said mixture to the engine jacket.

2. The method of engine cooling which consists in passing a cooling liquid through the engine jacket, dividing the liquid leaving the jacket into two portions, reducing the pressure of the liquid in one of said portions and thereby converting some of that portion into vapor, condensing said vapor, mixing the resultant liquid of condensation and the unvaporized residue of said one portion of the liquid with the other portion of the liquid in proportions varying automatically with the temperature at which the liquid leaves the jacket, and returning said mixture to the engine jacket.

3. In an engine cooling system, the combination with an engine cooling jacket having a top outlet, of a condenser, a connection from said outlet to the condenser comprising a continuously restricted portion, and means for normally maintaining such a pressure differential at opposite sides of said restricted portion that some of the cooling liquid passing through said portion will flash into vapor, said means comprising a pump for passing liquid from the bottom of the condenser into said jacket, and a bypass about the condenser connecting said top connection at the inlet side of said restricted portion to the inlet of the pump.

4. In an engine cooling system, the combination with an engine cooling jacket having a top outlet, of a condenser, a connec-

tion from said outlet to the condenser comprising a continuously restricted portion, and means for normally maintaining such a pressure differential at opposite sides of said restricted portion that some of the cooling liquid passing through said portion will flash into vapor, said means comprising a pump for passing liquid from the bottom of the condenser into said jacket, and a ⁵ regulable bypass about the condenser connecting said top connection at the inlet side of said restricted portion to the inlet of the pump.

5. In an engine cooling system, the combination with an engine cooling jacket having a top outlet, of a condenser, a connection from said outlet to the condenser comprising a continuously restricted portion, and means for normally maintaining such ¹⁰

a pressure differential at opposite sides of said restricted portion that some of the cooling liquid passing through said portion will flash into vapor, said means comprising a pump for passing liquid from the bottom ²⁰ of the condenser into said jacket, a bypass about the condenser connecting said top connection at the inlet side of said restricted portion to the inlet of the pump, and thermostatic means regulating the relative portions of the liquid leaving the jacket which ²⁵

pass through the condenser and bypass respectively.

6. The method of engine cooling which comprises passing a cooling liquid in liquid ³⁰ form from the engine cooling jacket to and through a condenser, subjecting the liquid passing through the condenser to a substantially continuous cooling and deaerating action, and returning the cooled and deaerated liquid to the engine jacket.

7. In an engine cooling system comprising an engine cooling jacket and a condenser, means for passing a cooling liquid in liquid form through said cooling jacket and back to the latter through said condenser, and means for subjecting the cooling liquid passing through said condenser to a substantially continuous deaerating action.

Signed at New York in the county of New York and State of New York this 22nd day of March, A. D. 1923.

HARRY C. MALLORY.
